UNITED STATES PATENT OFFICE

WARREN K. LEWIS, OF NEWTON, MASSACHUSETTS, ASSIGNOR TO STANDARD OIL DEVELOPMENT COMPANY, A CORPORATION OF DELAWARE

METHOD AND APPARATUS FOR DISTILLATION CONTROL

Application filed March 31, 1928. Serial No. 266,135.

This invention relates to an apparatus for determining the lowest boiling constituents of a mixture of hydrocarbons and to a method and apparatus for determining and regulating the lowest boiling constituents of the bottoms obtained on fractionating petroleum oils.

Fig. 1 of the drawing is a vertical plan with parts in section showing a bank of stills 10 for the fractional distillation of petroleum oils combined with a control apparatus pursuant to my invention, and

Fig. 2 is a horizontal plan of part of Fig. 1, and

Fig. 3 is a vertical cross section through a preferred form of apparatus which I have devised for determining the boiling point of the lowest boiling constituents of a mixture of hydrocarbons.

20 In accordance with my method, I automatically and periodically or continuously divert a minor part of the bottoms, the composition of which is to be controlled, partially distill the part diverted under conditions of substantially constant heat input and measure the temperature of the vapor produced. This vapor is preferably rectified under substantially constant conditions and the temperature measured subsequent to rectification. In

30 either event, the temperature of the vapor furnishes a regular or continuous indication of the lowest boiling constituents present in the bottoms. I may utilize this indication as a basis for the manual control of the major

35 distillation making such corrections manually as are necessary to hold the said major distillation to a predetermined separation but my preferred method is to make the control of the major distillation entirely automatic by utilizing the temperature of the vapor produced in the said control distillation

40 operating through suitable mechanism, to continuously or periodically modify the factors affecting the major distillation in order

45 to check divergences from the predetermined point and restore the system thereto. Devices to prevent over-correction or "hunting" may be employed.

My invention will be clearly understood 50 from the following exposition of my method

and of the apparatus by which the same may be carried into effect.

Referring specifically to Fig. 1—1, 2, 3, 4 and 5 represent the individual units of a battery of stills employed in the continuous distillation of petroleum oils. These stills are shown carried in the settings 1a, 2a, 3a, 4a and 5a. They may be heated in any suitable manner. Crude oil is supplied to 1 through the feed line 6 and is heated and partially vaporized in 1. The vapor passes into the rectifying column 1b in which it is rectified under conditions of partial condensation and thereafter passes off through the vapor line 1c. The remnant oil flows continuously from 1 through the pipe 7 into the still 2 in which it is further partially vaporized. The vapor so produced is rectified in the column 2b to produce an overhead vapor which is diverted from the system through the vapor line 2c. 70 The remnant crude oil passes from still 2 to still 3 through the oil line 8. It is again partially vaporized in still 3 and the vapor produced is rectified in the rectifying column 3b to produce an overhead vapor which is diverted from the system through the vapor line 3c. It will be assumed, by way of practical example, that the stills 1, 2 and 3 are operating to remove gasoline from a crude oil and that the removal has been nearly completed in the still 3, leaving a bottoms containing only a small quantity of gasoline which is conducted away through the pipe 9. It will, of course, be understood that any corresponding system for removing gasoline or 80 a first distillate from a petroleum oil may be similarly employed and that the use of a number of stills operating in series or of rectifying columns or other devices to improve the fractional separation is entirely optional. 85 In order to effect the maximum possible recovery of gasoline while accurately controlling the end point or final boiling point of the gasoline produced, the oil withdrawn from still 3 through the pipe 9 is diverted to 90 still 4 in which the final separation between gasoline and residuum is carefully controlled and which is termed a "cut" still. To further facilitate the separation, this oil is introduced to the still by discharging it into 95 100

the mid-section of the rectifying column 4b which communicates with the "cut" still. The oil may be elevated into the column 4b by the use of a steam lift consisting of the down flowing and up flowing sections of the pipe 9 and the steam jet 9a. Any equivalent transferring device, such as a pump, may be alternatively employed.

The "cut" still is usually operated with a higher reflux ratio and a lower output overhead than the preceding stills in the series. Partial condensation for the rectifying tower 4b is provided by flowing a cooling medium through the coil 4d in the upper part of said tower. The final fraction of gasoline vapor after rectification in column 4b passes off through the vapor line 4c. The residue crude oil, substantially free from gasoline, passes off through the pipe 10 to the still 5 for further separation of higher boiling point distillates, such as kerosene.

The rectifying columns, hereinbefore described, are all equipped with transverse partitions, overflow pipes and vapor distributors or corresponding means to promote the countercurrent contact of ascending vapor and descending condensate.

The apparatus 11 which I have devised is attached to and placed in communication with the flow line 10 by coupling it to the flange 12 of the T 13, which is a standard pipe fitting in the said flow line 10. The apparatus 11 serves to constantly measure the boiling point of the lowest boiling constituents of the bottoms flowing through the pipe 10. This temperature may be observed by means of a thermometer or any other equivalent measuring device and may, as previously stated, furnish the basis for the manual control of the still 4 but the temperature is preferably measured by means of a thermocouple 14 in the path of the vapor generated in the control still and the E. M. F. developed by the said thermocouple is transmitted through the leads 15 and 16 to the instrument box 17. The instrument box 17 receives an unmodified current either alternating or direct and preferably at one of the generally available voltages, through the leads 18 and 19 and 50 delivers a current through the leads 20, 21 and 22.

The temperature of the lowest boiling constituents as shown by the control still, which it is desired to retain in the bottoms, is then determined by experiment or as the result of previous runs in the apparatus or in any other suitable manner.

The instrument box 17 is adjusted so that any variation upwardly from this temperature or corresponding increase in the E. M. F. generated in the thermocouple 14 operating through the instrument box 17, will set up a modified current through the leads 20, 21 and 22 having certain characteristics, while 65 a deviation downwardly from the said pre-

determined temperature and corresponding decrease in E. M. F. of the thermocouple 14, will set up converse changes in characteristics of the modified current flowing through the leads 20, 21 and 22. This modified current may, for example, control the burner heating the still 4 in such a manner that if the boiling point of the lowest boiling constituents of the bottoms, indicated by the control still, is too low, the heat supplied to the still is increased until this condition is corrected; conversely, if this temperature is too high, the heat supplied to the still is decreased until the temperature measured by the thermocouple 14 has returned to the desired point. This control may be accomplished, for example, by the use of a gas burner controlled by motors such that when current is supplied to one of the motors by means of the leads 20 and 21, the motor operates to further open the valve controlling the supply of gas to the burner and supplies an additional amount of heat to the still 4, whereas a current flowing through the leads 21 and 22 operates a different motor which closes or partly closes the valve, controlling the supply of gas to the burner. It will, of course, be understood that any other method of regulating the major distillation may, pursuant to my invention, be combined with the apparatus 11 and controlled by it. A more detailed description of the instrument box 17 and the burner adjusting mechanism 23 is not given for the reason that such equipment may be easily designed or adapted to this purpose and the construction thereof is not a part of my invention.

The general arrangement of control apparatus 11 and still 4 appears in horizontal plan in Fig. 2.

Referring specifically to Fig. 3, the control apparatus comprises the hood or casing 24 provided with a top closure 25 preferably threaded thereto. The casing 24 carries a flange 24a at the lower end adapted to cooperate with the flange 12 of the T 13 to place the said casing in free communication with a flow line 10 which conducts the bottoms from the still 4 to the still 5.

The casing 24 is surrounded by the thermal insulation 24b. Within the casing 24 and suspended from the top closure 25 is the control still 28 and ancillary apparatus. The control still 28 receives a substantially continuous supply of oil from the body of still bottoms 29, which surrounds it, by means of the sharp-mouthed orifice meter 30. The still bottoms accumulates in the control still 28 up to the level 31, any excess passing off continuously through the overflow 32 provided with the trap 34. The heating element, located in the control still 28, may be of any suitable type but preferably consists of an electrical resistance 35 in a metal casing 36 supplied with current by means of the leads

37 and 37a. These leads may be carried to the exterior between the flanges 12 and 24a and gasketing means may be employed between the flanges which means is grooved or cut to permit the leads to extend to the exterior.

While the amount of heat supplied to the control still may vary over considerable limits, I preferably maintain it substantially constant and this may be effected by supplying suitable electric current to the heating element from any electric circuit of substantially constant voltage. The amount of heat supplied is sufficient to partially vaporize the still bottoms in 28. The vapor ascends the column 27 which is preferably packed with a divided material presenting considerable surface such as short sections of tubing 38 to facilitate rectification. The column 27 is preferably surrounded by thermal insulation 29. To further improve the rectification which takes place in the column 27, I preferably partially condense vapor at or near the top of the column 27 and this partial condensation is preferably accomplished under conditions so controlled as to provide a substantially constant reflux. The specific partial condensing apparatus which I prefer for this purpose comprises the receptacle 40 receiving a low boiling point liquid such as water through the inlet 41 and provided with the outlet 42 through which any excess, above that necessary to maintain a definite level, is diverted.

The substantially continuous and controlled supply of the low boiling point liquid is passed by means of the sharp-mouthed orifice 43 into the evaporator 44. The low boiling liquid is so chosen that it will be evaporated in 44 at the temperature of condensation of the hydrocarbon vapor in the column 27 and is supplied in such a quantity that it will be completely evaporated. The vapor products of evaporation escape through the outlet 45. I achieve in this manner a reflux in the column which is substantially independent of the temperature of the liquid introduced to the partial condenser 44. The rectified hydrocarbon vapor passes from the control column 27 by means of the vapor outlet 46 communicating with the vapor duct 47. Outlet 46 is preferably surrounding by thermal insulation 46a. The thermocouple 14 for measuring the temperature of the rectified vapor is preferably placed in the vapor duct 46 so that the junction 14a is directly in the path of the issuing vapor at a point at which the said vapor has had no opportunity to cool. While the vapor, after passing the thermocouple 14, may be vented in any way, I preferably condense it by passing a cooling liquid in indirect heat exchange relationship therewith, using for this purpose the condenser 48 and after condensation combine it with the excess liquid passing from the con-

trol still 28 through the overflow pipe 34, thereafter diverting the stream of liquid to an accumulator through the pipe 49.

The space between the insulation 29 surrounding the rectifying column of the control still 27 and the casing 24 is in free communication with the oil flowing in the pipe 10 and this being at an elevated temperature operates to minimize loss of heat from the column 27. The vent 49a connects this space with the pipe 49 to prevent the same from becoming gas bound and to provide a circulation of hot oil about the column 27 in addition to that maintained by convection and turbulence resulting from the flow of oil in the pipe 10.

In my preferred method of operation, I maintain a substantially constant thermal gradient between the finally rectified vapor and a point immediately beneath the partial condenser in the rectifying column 4b, notwithstanding variations taking place in the still 4. In order to accomplish this, I measure the temperature of the finished overhead vapor leaving the column 4b shown on Fig. 1, by means of thermocouple 50. I also measure the temperature of the contents of the column at a point beneath the partial condenser 4d by means of thermocouple 51, which may be located at any suitable point in the column although it is preferably placed in or immediately above the liquid on the topmost plate. The E. M. F.'s generated in thermocouples 50 and 51 are carried by suitable leads to the instrument box 52, which in turn receives an unmodified current from any suitable source by means of the leads 53 and 54.

The instrument box is adjusted to maintain a substantially constant differential temperature between the two points in the column at which the respective thermocouples are located. Any greater difference between the E. M. F.'s of the respective thermocouples will set up a modified current flowing through the leads 55, 56 and 57 having certain characteristics and any decrease in the difference between the E. M. F.'s of the respective thermocouples will set up a modified current flowing through the said leads, having the converse characteristics. This modified current operating through suitable control mechanism 58 varies the amount of cooling fluid passing through the partial condenser 4d so as to increase the amount of partial condensation if the temperature differential between the points at which the thermocouples are located is not sufficiently great and to diminish the amount of partial condensation in case it is too great. In this manner, a substantially constant rectifying effect is obtained in the column notwithstanding variations in the amount of vaporization in the still 4.

The foregoing description is for purposes of illustration. My method may be carried

out in apparatus other than that specifically described and it is my intention that the invention be limited only by the appended claims or their equivalents, in which I have endeavored to claim broadly all novelty inherent in the invention.

I claim:

1. The method of controlling the lowest boiling point constituents of bottoms obtained on a fractional distillation of petroleum oils, which comprises continuously abstracting at a substantially uniform rate a minor part of the bottoms to be controlled, heating same under conditions of substantially uniform heat input to produce vapor and an unvaporized residuum, rectifying the vapor produced, measuring the temperature of the rectified vapor, and modifying the condition of the first mentioned distillation to the extent necessary to hold such temperature near a predetermined point.

2. The method of controlling the lowest boiling constituents of bottoms produced on the fractional distillation of petroleum oils, which comprises continuously abstracting at a substantially uniform rate a minor part of the bottoms to be controlled, heating same under conditions of substantially uniform heat input to produce vapor and an unvaporized residuum, conducting away unvaporized residuum, rectifying the vapor produced under conditions adapted to maintain a substantially constant reflux, measuring the temperature of the rectified vapor produced, and modifying the condition of the first mentioned distillation to the extent necessary to hold such temperature near a predetermined point.

3. The method of controlling the lowest boiling point constituents of bottoms obtained on the fractional distillation of petroleum oils, which comprises continuously abstracting a minor part of the bottoms to be controlled, heating same under conditions of substantially uniform heat input to produce vapor, and an unvaporized residuum, measuring the temperature of the vapor produced, causing variations of such temperature to automatically alter the conditions affecting the first mentioned distillation to the extent necessary to hold the said temperature near a predetermined point.

4. The method of controlling the lowest boiling point constituents of bottoms obtained on the fractional distillation of petroleum oils, which comprises continuously abstracting at a substantially uniform rate a minor part of the bottoms to be controlled, heating same under conditions of substantially uniform heat input to produce vapor and an unvaporized residuum, rectifying the vapor produced, measuring the temperature of the rectified vapor and causing variations of such temperature to automatically alter the conditions affecting the first mentioned

distillation to the extent necessary to hold the said temperature near a predetermined point.

5. The method of controlling the lowest boiling point constituents of bottoms produced on the fractional distillation of petroleum oils, which comprises continuously abstracting at a substantially uniform rate a minor part of the bottoms to be controlled, heating same under conditions of substantially uniform heat input to produce vapor and an unvaporized residuum, conducting away unvaporized residuum, rectifying the vapor produced under conditions adapted to maintain a substantially constant reflux, measuring the temperature of the rectified vapor produced and causing variations of such temperature to automatically alter the conditions affecting the first mentioned distillation to the extent necessary to hold the said temperature near a predetermined point.

6. The method of controlling the lowest boiling point constituents of bottoms obtained on the fractional distillation of petroleum oils, which comprises continuously abstracting a minor part of the bottoms to be controlled, heating same under conditions of substantially uniform heat input to produce vapor and an unvaporized residuum, interposing a thermocouple in the path of the vapor produced and causing variations in the E. M. F. generated in said thermocouple from a predetermined point to actuate modifications in the condition of the first mentioned distillation necessary to hold such E. M. F. near a predetermined point.

7. The method of controlling the lowest boiling point constituents of bottoms obtained on the fractional distillation of petroleum oils, which comprises continuously abstracting a minor part of the bottoms to be controlled, heating same under conditions of substantially uniform heat input to produce vapor, and an unvaporized residuum, measuring the temperature of the vapor produced, rectifying the vapor produced, interposing a thermocouple in the path of the rectified vapor and causing variations in the E. M. F. generated in said thermocouple from a predetermined point to actuate modifications in the condition of the first mentioned distillation necessary to hold such E. M. F. near a predetermined point.

8. The method of controlling the lowest boiling point constituents of bottoms obtained on the fractional distillation of petroleum oils, which comprises continuously abstracting a minor part of the bottoms to be controlled, heating same under conditions of substantially uniform heat input to produce vapor and an unvaporized residuum, rectifying the vapor produced under conditions adapted to maintain a substantially constant reflux, interposing a thermocouple in the path of the rectified vapor and causing variations in the E. M. F. generated in the

said thermocouple from a predetermined point to actuate modifications in the condition of the first mentioned distillation necessary to hold such E. M. F. near a predetermined point.

9. The method of controlling the fractional distillation of petroleum oils, which comprises heating petroleum oil to produce vapor and a bottoms, rectifying the vapor produced in a rectifying zone under conditions of partial condensation, continuously abstracting a minor part of the bottoms, heating the abstracted part under conditions of a substantially uniform heat input to produce vapor and an unvaporized residuum, measuring the temperature of the vapor produced, causing variations of the measured temperature from a predetermined point to automatically alter the conditions affecting the first mentioned distillation to the extent necessary to hold the said temperature near a predetermined point and maintaining a constant differential between the temperature of the rectified vapor produced by the first mentioned distillation and an intermediate point in the said rectifying zone.

10. An apparatus for controlling the lowest boiling point constituents of bottoms obtained on the fractional distillation of petroleum oils, which comprises means for abstracting a minor part of the bottoms to be controlled at a substantially uniform rate, means for heating the abstracted part under conditions of substantially uniform heat input to produce vapor and an unvaporized residuum, means for conducting away unvaporized residuum, means for separately conducting away the vapor produced, means for measuring the temperature of the vapor produced, and means for causing variations of the measured temperature from a predetermined point to automatically alter the conditions affecting the first mentioned distillation to the extent necessary to hold the said temperature near a predetermined point.

11. An apparatus for controlling the lowest boiling point constituents of bottoms obtained on the fractional distillation of petroleum oils, which comprises means for abstracting a minor part of the bottoms to be controlled at a substantially uniform rate, means for heating the abstracted part under conditions of substantially uniform heat input to produce vapor and an unvaporized residuum, means for conducting away unvaporized residuum, means for rectifying the vapor produced, means for measuring the temperature of the rectified vapor, and means for causing variations of the measured temperature from a predetermined point to automatically alter the conditions affecting the first mentioned distillation to the ex-

tent necessary to hold the said temperature near a predetermined point.

12. An apparatus for controlling the lowest boiling point constituents of bottoms obtained on the fractional distillation of petroleum oils, which comprises means for abstracting a minor part of the bottoms to be controlled at a substantially uniform rate, means for heating the abstracted part under conditions of substantially uniform heat input to produce vapor and an unvaporized residuum, means for conducting away unvaporized residuum, means for rectifying the vapor produced, means for maintaining a substantially constant reflux during the rectification of said vapor produced, means for measuring the temperature of the rectified vapor, and means for causing variations of the measured temperature from a predetermined point to automatically alter the conditions affecting the first mentioned distillation to the extent necessary to hold the said temperature near a predetermined point.
